DESIGN FOR A LIQUID SPRAYER

Paul A. Bury, Cincinnati, Ohio

Application December 7, 1943, Serial No. 111,941

Term of patent 14 years

To all whom it may concern:

Be it known that I, Paul A. Bury, a citizen of the United States and resident of Cincinnati, county of Hamilton, and State of Ohio, have invented a new, original, and ornamental Design for Liquid Sprayers, of which the following is a specification, reference being had to the accompanying drawing, forming a part thereof, and in which:

Figure 2 is a perspective view thereof; and Figures 3 and 4 are enlarged transverse sectional views taken respectively on the lines 3—3 and 4—4 of Figure 1.

I claim:

The ornamental design for a liquid sprayer, substantially as shown.

PAUL A. BURY.
